WILHELM PAPE, OF BERLIN, GERMANY, ASSIGNOR TO BERGMANN-ELEKTRICITÄTS-
WERKE, AKTIENGESELLSCHAFT, OF BERLIN, GERMANY, A CORPORATION

HIGH-PRESSURE STEAM TURBINE

Application filed February 10, 1925, Serial No. 8,250, and in Germany February 22, 1924.

This invention relates to high-pressure steam turbines and consists in an improvement, whereby the high-pressure part of the turbine is constructed as drum turbine and the medium pressure part as wheel-turbine. By this arrangement a number of advantages are obtained, as pointed out in the specification.

The known steam-turbine constructions operate either in all pressure stages with even pressure or with over-pressure, or even pressure stages are provided in the high-pressure part and adjacent to these there are over-pressure stages. If the turbine is constructed for high steam pressure, it is advisable in order to obtain a high efficiency, to keep the blade diameter in the range of highest pressure as small as possible. The reason for this is found therein, that for a given volume of steam a greater height of the turbine blades will be necessary. The clearance space will therefore become smaller with respect to the height of the blades and accordingly the losses due to clearance leakage will be decreased. Furthermore a smaller diameter of the blade rim will also cause a reduction in the losses due to friction and ventilation.

According to my invention the parts of the turbine which are under the highest pressure are preferably constructed as drum turbine. In order to obtain the smallest diameter of the blade rim and a number of stages which is not too great, the speed of rotation of the high-pressure part of the turbine may be chosen higher than that of the subsequent stages. The high-pressure part is in this case arranged upon a special shaft, which is either connected with the shaft of the low-pressure part by means of a gear or which may be separated from the low-pressure part and drive a separate working machine.

In general the drum will have to be constructed with blades for over-pressure. Eventually, however, the drum may also be constructed with blades for even pressure. The employment of over-pressure blades results in the especial advantage, that the relative velocity of the steam in the blades becomes smaller. This is of especial importance within the range of highest pressure in

order to obtain a high efficiency of the turbine, because the energy losses in the blades will become smaller with smaller steam velocities in the channel.

Quite different are the conditions within the range of medium pressure in the turbine, that is to say in the stages subsequent to the high pressure parts. In this case the height of the blades in view of the greater volume of steam for the diameter of the blade rim in the high-pressure part become too large and it will therefore be necessary to increase the diameter of the blade rim. For the greater diameter it would, however, be a disadvantage to retain the drum construction adapted for the high-pressure part, since this would cause impermissibly high clearance losses. Within this range of pressure, therefore, according to my invention the turbine is constructed as wheel-turbine, so that the tightening between the stages may again be accomplished as much as possible in proximity to the shaft.

For the new turbine according to my invention it is therefore essential, that the high-pressure part is constructed as drum-turbine, while the adjoining stages of the turbine are constructed as wheel-turbine. The wheel-turbine may thus comprise all stages following the high-pressure part, and therefore also the entire low-pressure part. In the low-pressure part, however, the clearance losses on account of the smaller density of the steam, are no more of importance and therefore, for the low-pressure part eventually also a drum-turbine with large diameter may be employed.

In the drawing I have shown two examples of carrying out my invention. According to Fig. 1 the turbine consists of the high-pressure part *a* and the medium-pressure part *b*, whereby the former is constructed as drum-turbine and the latter as wheel-turbine, which are both mounted upon the same shaft. In the construction according to Fig. 2, however, the high-pressure part *a* is mounted separately upon a shaft and the low-pressure part *c* is constructed as drum-turbine, so that only the medium pressure part *b* of the tur-

bine is constructed as wheel-turbine, which is located between the two drum-turbines.

I claim:

A high pressure steam turbine comprising
5 a drum turbine for the high pressure stages,
a drum turbine for the low pressure stages,
and a wheel turbine for the medium pressure
stages, said wheel turbine being arranged in-
termediate said drum turbine and immediate-
10 ly adjacent the high pressure stage.

In testimony whereof I have affixed my
signature.

WILHELM PAPE.
